(57) **CLAIM**

The ornamental design for a glove as shown and described.

DESCRIPTION

FIG. 1 is a top-perspective view of a glove for a right hand, a left-hand glove also claimed being a mirror image for all figures, according to my ornamental design;

FIG. 2 is a left-side elevation view thereof;

FIG. 3 is a top-palmer-plan view thereof;

FIG. 4 is a right-side elevation view thereof;

FIG. 5 is a bottom-dorsal-plan view thereof;

FIG. 6 is a rear-elevation view thereof; and,

FIG. 7 is a front-elevation view thereof.

The broken lines in the figures depict portions of the article and form no part of the claimed design.
